UNITED STATES PATENT OFFICE

135,990

DESIGN FOR A HANDBAG

Earl Gresh, St. Petersburg, Fla.

Application October 16, 1942, Serial No. 108,545

Term of patent 3½ years

To all whom it may concern:

Be it known that I, Earl Gresh, a citizen of the United States, residing at St. Petersburg, in the county of Pinellas and State of Florida, have invented a new, original, and ornamental Design for Handbags, of which the following is a specification, reference being had to the accompanying drawing, forming part thereof.

Fig. 1 is a top plan view of a handbag showing my new design.

Fig. 2 is a side elevational view thereof.

Fig. 3 is an end elevational view thereof.

The linings on the drawing indicate contrasting colored areas.

I claim:

The ornamental design for a handbag, as shown and described.

EARL GRESH.
